UNITED STATES PATENT OFFICE.

RUDOLPH C. SMITH, OF YONKERS, NEW YORK, ASSIGNOR TO OTIS BROTHERS & COMPANY, OF NEW YORK.

ELEVATOR.

SPECIFICATION forming part of Letters Patent No. 439,734, dated November 4, 1890.

Application filed April 24, 1888. Serial No. 271,684. (No model.) Patented in England September 26, 1888, No. 13,890.

To all whom it may concern:

Be it known that I, RUDOLPH C. SMITH, a citizen of the United States, residing at Yonkers, county of Westchester, and State of New York, have invented certain new and useful Improvements in Elevators, fully described and represented in the following specification and the accompanying drawings, forming a part of the same, the said improvements being embraced in British Letters Patent No. 13,890, dated September 26, 1888.

This invention relates to a means for operating the valve or other device which controls the movements of an elevator-car.

In the accompanying drawings, Figure 1 is an elevation, partly in section, of a hydraulic elevator equipped with valve-operating devices embodying the present invention. Figs. 2 and 3 are enlarged views of portions of Fig. 1. Fig. 4 is a plan view of the parts shown in Fig. 2. Fig. 5 is a similar view of the parts shown in Fig. 3. Figs. 6 and 7 are views of modifications of some of the devices.

Referring to said figures, it is to be understood that A represents the elevator-car, and B the hoising-cable. The elevator, as herein shown, is operated by means of a vertical hydraulic cylinder C, having a piston, the rods a of which are connected to a pulley b, which travels in the depending loop of the hoisting-cable B. The cylinder C is provided with the usual induction-pipe c, through which water is admitted to the upper end of the cylinder under suitable pressure to drive the piston, and with a circulating-pipe d and discharge-pipe f, through which the water circulates from the upper to the lower end of the cylinder as the car descends and from which the water is finally discharged as the car again ascends, all of these parts being organized in the common and well-known manner.

The movements of the car are controlled by an ordinary valve D, which controls the circulation and discharge of the water in the common manner. The rod g of the valve D is provided with an auxiliary piston h, which works in a small auxiliary cylinder k, having ports which are controlled by an auxiliary valve l, the rod m of which is connected to a

lever n, which is fulcrumed upon the rod g. The water for operating the piston h is admitted to the cylinder k through an induction-port o, which communicates through a pipe (not shown) with the circulating-pipe d or any other source of water-supply, and the water after performing its work in the cylinder k is exhausted through a discharge-pipe p.

Connected to one end of the lever n is a pair of ropes s s', which extend in opposite directions, and after passing around suitably-arranged pulleys t extend upward in the elevator-shaft, passing through or adjacent to the car, and are secured at their upper ends to a movable bar w, located at the top of the elevator-shaft. The bar w moves vertically in a straight or substantially straight line in a guide and is connected by a pin to a lever y, which is fulcrumed upon a suitable support, and the opposite end of which is provided with a sufficient weight z to maintain the ropes s s' under proper tension to operate the valve l whenever the tension of one of the ropes is increased beyond that of the other, as will be hereinafter explained, the bar w and the means shown, or any other suitable means for holding it in position to maintain the ropes under tension, constituting an equalizer, of which the bar w is a movable member. It is evident that the form of the movable member and the means for holding it under tension may be varied.

As shown in Figs. 1, 3, and 5, there are fixed studs projecting from the side of the car, upon which are mounted deflecting-pulleys 9, which are arranged in such positions that as the car moves up and down the pulleys will travel just outside the ropes s. Located above the pulleys 9 and between the ropes s s' is a vibrating or moving deflecting-pulley 10, which is mounted upon one arm of a bell-crank lever 12, which is fulcrumed upon the side of the car, and has its other arm provided with a stud 13, which passes through an opening in the side of the car and enters a slot formed in a hand-lever 14, also fulcrumed upon the car in position to be conveniently operated by the conductor.

The operation of the apparatus as thus far described is as follows: So long as the lever

14 remains in its normal position the pulley 10 will remain in the central position indicated in Fig. 1 and neither one of the ropes *s* *s'* will be deflected. The length of the ropes 5 is so adjusted that when in this position the valve *l* will be held in its mid-position, as indicated in Fig. 1, so as to prevent the induction and discharge of water to and from the cylinder *k*, and as a consequence the piston *h* 10 and the main valve *D* will remain in their mid-position and the car will be at rest. To cause the car to ascend, the lever 14 will be moved downward, thereby rocking the lever 12, so as to carry the pulley 10 to the left, as indicated by dotted lines in Fig. 3, and cause it 15 to press against and deflect the ropes *s* *s'* upon that side against one of the pulleys 9. The rope *s*, thus deflected around the pulley 10 against the pulley 9, will be put under sufficient 20 tension to draw the bar *w* down against the resistance of weight *z*, and this downward movement of the bar *w* will permit the undeflected rope to follow the deflected rope around the pulleys *t*, the lever *n* moving downward. The bar *w* and the lever *n* thus move 25 downward together, the bar *w* moving sufficiently to compensate for the shortening of the deflected rope. It is apparent, however, that the compensating movement of the bar 30 *w* will be but one-half the length of the rope taken up by the deflecting-pulleys, as this shortening is compensated for on two sides by the movement of the bar *w*, acting upon both the ropes *s* *s'*. The weight *z* is so adjusted 35 as to permit the movement of the bar *w* on the shortening of the deflected rope, but to operate to equalize the tension upon the two ropes and maintain a sufficient tension upon them to prevent any slack in the undeflected rope as the other rope is deflected. This 40 movement of the ropes around the pulleys *t* will rock the lever *n* downward and move the valve *l* so as to admit water to the lower end of the cylinder *k* and permit the water in the 45 upper end of the cylinder to be discharged. This will operate to move the piston *h* and the main valve *D* upward, so as to permit the water in the lower end of the cylinder *C* to escape through the discharge-pipe *f* and cause 50 the car to ascend. As soon as the piston *h* and main valve commence to move upward, as just described, the rod *g*, acting upon the lever *n*, will operate to move the valve *l* back toward its mid-position, and as the movement 55 of the piston *h* and valve *D* continue the valve *l* will be carried back to its mid-position, so as to prevent the further admission of water to the cylinder *k*, and thus arrest the piston *h* and the main valve. The amount of movement 60 thus given to the main valve will thus always be dependent upon and proportioned to the amount of movement given to the auxiliary valve *l*, and by this means the conductor, by moving the lever 14 so as to open the valve 65 *l* to a greater or less extent, can control the extent of movement of the main valve *D*, and

thus control the speed of the car. The main valve having been moved upward, as just described, so as to cause the car to ascend, it is only necessary in order to stop the car to release the lever 14. As soon as this is done the pulley 10 will assume its central position, thereby releasing the rope *s*, which has been deflected around the pulley and against the pulley 9, and as this takes place the weight *z*, 70 acting through the lever *y*, will operate to raise the bar *w* and return the ropes to their normal position, thus shifting the ropes around the pulleys *t* in the reverse direction, and thereby rocking the lever *n*, so as to shift 75 the valve *l* and admit water above the piston *h* and allow the water below the piston to be discharged. This will cause the piston *h* and main valve to move downward until they arrive in their mid-position, and this downward movement will through the lever *n* operate to move the auxiliary valve *l* back to its mid-position, so as to arrest the movement of the main valve as soon as the latter has arrived 80 at its mid-position, and thus stop and retain 85 the car in that position.

To cause the car to descend and to arrest it during its descent, the operation is exactly the same as just described, except that the lever 14 will be rocked in the reverse direction, deflecting the rope *s'*. 90

It might sometimes happen that the auxiliary valve would bind or stick in its valve-chest to such an extent that the weight *z* would not be sufficient to operate it, as just described, and in case this should happen it is desirable to provide means by which the conductor can exert the power of the lever 14 directly upon the valve. For this purpose the lever *y* is provided with a pawl 15, which engages with a ratchet 16, formed upon a segment 17, which is pivoted loosely at the side of the lever *y*. The segment 17 is provided with a slot 18, into which extends a pin 19, which projects from a stationary arm 20. The slot 18 is of sufficient length to allow the necessary movement of the segment occasioned by the downward movement of the bar *w* in the deflection of the ropes *s* *s'* when the valve *l* moves freely and responds to the weight *z*. 105 If, however, at any time the valve fails to respond to the weight *z*, the bar *w* will be moved downward by the deflection of one of the ropes around the pulley 10 and the weight *z* raised until the pawl 15, engaging with the ratchet 16, rocks the segment 17 into engagement with the stud 19. The lever *y* and the bar will then be locked against further movement in that direction, and any further strain upon the rope by the pulley 10 will act directly 110 to move the auxiliary valve.

Any elongation of the ropes *s* *s'* occasioned by heat or by stretching in use will be taken up by the weight *z*, which will rock the lever *y* so as to raise the bar and maintain the 115 ropes under proper and equal tension. As the lever *y* is thus rocked the pawl 15 will be

retracted on the ratchet 16 and engage with the ratchet in a new position, so as to maintain the proper connection between the segment and the lever y . The slot 18 is of sufficient length to allow the lever y to be rocked in the opposite direction to accommodate itself to any contraction in the ropes occasioned by cold. The bar w is provided with a number of openings, as indicated, by which it can be connected to the lever y at different points to accommodate itself to longer or shorter ropes.

It will be observed that the levers 12 14 are so constructed as to form a compound lever, which operates so that as the lever 12 is rocked to deflect either one of the ropes $s s'$ the power exerted by the lever 14 is, owing to the change in the angles of the levers, gradually increased, thus compensating for the gradually increasing resistance of the ropes as its deflection is increased.

The devices for deflecting the ropes $s s'$ (shown in Figs. 1, 3, and 5) may be modified without departing from my invention. Thus, as shown in Fig. 6, the pulley 10' may be mounted on a fixed stud projecting from the side of the car, while the pulleys 9' may be mounted upon a bell-crank arm pivoted to the stud on which the pulley 10' is mounted; or, as shown in Fig. 7, they may be mounted upon a slide, the bell-crank arm and slide being moved through suitable connections by the lever 14, as shown. In each of these modifications the pulleys 9' operate to deflect one of the ropes $s s'$ as they are moved either to the right or the left, as desired. Other modifications may readily be made by persons skilled in this art without departure from my invention.

The apparatus is herein shown as applied to operate an auxiliary valve; but it is to be understood that it may be applied to the main valve directly or to operate any other mechanism for controlling the movements of the elevator-car—such, for example, as a belt-shifter, a steam-valve, or any of the other appliances used in connection with elevators.

What I claim is—

1. The combination, with an elevator-car and the mechanism for controlling its movements, of the two ropes $s s'$, connected to the controlling mechanism, deflecting-pulleys carried by the car for deflecting one or the other of said ropes, and an equalizer provided with a movable member from which the ropes are suspended, the equalizer yielding to permit the movement of the movable member to compensate for the shortening of the deflected rope and returning the ropes to their normal position when the deflected rope is released, substantially as described.

2. The combination, with an elevator-car and the mechanism for controlling its movements, of the two ropes $s s'$, connected to the controlling mechanism, one moving and two fixed deflecting-pulleys carried by the car for deflecting one or the other of said ropes, and

an equalizer provided with a movable member from which the ropes are suspended, the equalizer yielding to permit the movement of the movable member to compensate for the shortening of the deflected rope and returning the ropes to their normal position when the deflected rope is released, substantially as described.

3. The combination, with the elevator-car and the mechanism for controlling its movements, of the two ropes $s s'$, connected to the controlling mechanism, deflecting-pulleys carried by the car for deflecting one or the other of said ropes, a compound lever 12 14 for operating said deflecting-pulleys, and an equalizer provided with a movable member from which the ropes are suspended, the equalizer yielding to permit the movement of the movable member to compensate for the shortening of the deflected rope and returning the ropes to their normal position when the deflected rope is released, substantially as described.

4. The combination, with an elevator-car and the mechanism for controlling its movements, of the two ropes $s s'$, connected to the controlling mechanism, deflecting-pulleys carried by the car for deflecting one or the other of said ropes, an equalizer provided with a movable member from which the ropes are suspended, the equalizer yielding to permit the movement of the movable member to compensate for the shortening of the deflected rope and returning the ropes to their normal position when the deflected rope is released, substantially as described.

5. The combination, with an elevator-car and the mechanism for controlling its movements, of two ropes $s s'$, connected to the controlling mechanism, deflecting-pulleys carried by the car for deflecting one or the other of said ropes, an equalizer provided with a movable member from which the ropes are suspended, the equalizer yielding to permit the movement of the movable member to compensate for the shortening of the deflected rope and returning the ropes to their normal position when the deflected rope is released, a stop, as 19, for limiting the movement of the movable member, substantially as described.

6. The combination, with the two ropes $s s'$, connected to the elevator-controlling mechanism, of an equalizer provided with a movable member connected to said ropes, said equalizer yielding to permit the movement of the movable member when the tension on either of the ropes is increased and returning the ropes to their normal position when the excess of tension on the rope is released, substantially as described.

7. The combination, with the two ropes $s s'$,

connected to the elevator-controlling mechanism, of an equalizer provided with a movable member connected to said ropes, said equalizer yielding to permit the movement of the movable member when the tension on either of the ropes is increased and returning the ropes to their normal position when the excess of tension on the rope is released, and a stop, as 19, for limiting the movement of the movable member, substantially as described.

8. The combination, with the ropes $s s'$, of

the bar w , lever n , weight z , segment 17, stop 10, and pawl and ratchet 15 16, substantially as described.

In testimony whereof I have hereunto set 15 my hand in the presence of two subscribing witnesses.

RUDOLPH C. SMITH.
